(57) **CLAIM**

The ornamental design for a pumpkin stacking connector, as shown and described.

DESCRIPTION

FIG. 1 is a perspective view of a pumpkin stacking connector, showing my new design, shown in a used condition with pumpkins and an additional pumpkin stacking connector shown in broken lines;

FIG. 2 is an enlarged top perspective view thereof;

FIG. 3 is a front elevational view thereof;

FIG. 4 is a rear elevational view thereof;

FIG. 5 is a left side elevational view thereof, the right side elevational view being a mirror image thereof;

FIG. 6 is a top plan view thereof;

FIG. 7 is a bottom plan view thereof; and,

FIG. 8 is a bottom perspective view thereof.

The broken lines showing pumpkins and an additional pumpkin stacking connector in FIG. 1 depict environmental matter and form no part of the claimed design.
